CHAISE LOUNGE OR SIMILAR ARTICLE

William Shelzi, 50 Chester Road, Lynbrook, N.Y.

Filed July 27, 1962, Ser. No. 71,070

Term of patent 14 years

(Cl. D15—11)

FIG. 1

FIG. 2

FIG. 3

FIG. 4

FIG. 5

FIG. 6

FIG. 1 is a top plan view of a chaise lounge, showing my new design;

FIG. 2 is a side elevational view thereof;

FIG. 3 is a top plan view thereof, with the back rest separated;

FIG. 4 is a front elevational view thereof;

FIG. 5 is a rear elevational view thereof, with the back rest removed;

FIG. 6 is a cross sectional view taken along lines 6—6 of FIG. 1 thereof.

The back surface of the head rest is plain.

I claim:
The ornamental design for a chaise lounge or similar article, substantially as shown and described.
